HIGH VOLTAGE TERMINAL CONSTRUCTION

Franklin S. Smith, Brooklyn, N. Y.

Application February 2, 1931, Serial No. 513,031

25 Claims. (Cl. 173—318)

This invention relates to high voltage terminal construction.

One of the objects of this invention is to provide a terminal construction that will be well adapted for outdoor service at high potentials, that will be of inexpensive construction, simple, and of dependable action. Another object is to provide a construction of the abovementioned character for use in connection with high voltage apparatus enclosed in a casing with a gaseous dielectric under high pressure, in which the possibility of leakage of gaseous dielectric under this high pressure is dependably precluded while at the same time reliable action of the high voltage terminal under varying weather conditions may be achieved. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing the single view is a central vertical sectional view through one of the various possible embodiments of my invention.

In the drawing there is indicated at 10 a portion of the wall of a casing, the latter being made preferably of pressed steel so as to withstand high pressures, within which is contained a high voltage apparatus which, by way of illustration, may take the form of a condenser diagrammatically indicated at 11 and one terminal of which is indicated at 12. The other terminal 13 is to be passed through the casing 10, which may be assumed to be positioned outdoors. The condenser 11 may be of any suitable construction for appropriate coaction with the gaseous dielectric under pressure contained in the casing 10; this dielectric, under a pressure on the order of fifteen atmospheres, may take the form of any suitable chemically neutral gas, such as nitrogen, for example. The conductor 13 is to be led through the casing in a manner so as to dependably preclude loss of the high pressure dielectric and also to permit the maintenance, dependably, of an electrical connection outside of the casing 10 under varying weather conditions met with in practice.

Casing 10 is provided with a suitable opening through which is passed a metallic bushing 14 whose flange 15 abuts against the inner face of the wall of the casing, bushing 14 being welded

to the wall 10, as at 16, to form a secure mechanical and sealed connection.

The upper end of bushing 14 is interiorly and exteriorly threaded as at 17 and 18, and supported by the portion 18 thereof is a metallic ring member 19 of substantial outside diameter and having formed in its upper surface an annular recess 20 within which is received the lower end 21^a of an insulator 21, the latter being tubular and tapered substantially as shown in the drawing. Insulator 21 is cemented into the recess 20 of ring 19 by any suitable cement indicated at 22, and if desired the surfaces of ring member 19 and of insulator 21 that are to contact with the cement may be suitably roughened or corrugated.

Insulator 21 is made of any suitable material that is well adapted to resist the action of such elements to which it is exposed when operating out-of-doors and conveniently it may be formed of suitable ceramic material such as porcelain, preferably glazed. At its upper end insulator 21 is closed by a disk-like plate 23 flanged as at 23^a so as to overlap laterally the upper portion 21^b of insulator 21, metallic disk member 23 being cemented to the portion 21^b of the insulator, as is indicated at 24. Here also the surfaces with which the cement is to contact may be appropriately roughened or corrugated if desired.

Extending centrally through the top plate 23 is a bolt 25, to the inner end of which is connected a high tension conductor 26 and to the outer end of which connection may be made, as by conductor 27, to the high tension circuit with which the apparatus within the casing 10 is to be associated.

The tube-like insulator 21 is of sufficient length in an axial direction safely to withstand the difference of potential existing between the connecting bolt 25 and the lower ring member 19 which is grounded to the casing 10 and preferably the upper and lower members 23 and 19 function as controlling members for the flux of the dielectric field set up by this difference of potential. Preferably, also, the member 21 is petticoated as at 21^c thus further to increase the potential at which flash-over might occur particularly when the outside surface of member 21 is wet, the petticoats 21^c substantially preventing the entire external surface of member 21 from becoming wet and also greatly lengthening the path of surface leakage in a direction from member 23 to member 19.

Member 21, preferably, as above noted, made of porcelain or the like, while well adapted for dependable functioning under the varying

weather conditions of outdoor installations, is relieved from being subjected to the relatively very great pressure of the gaseous dielectric by means of a combined insulating and sealing construction indicated as a whole at 28; this construction includes a metal bushing 29 in tight or sealed threaded engagement with the interior threaded portion 17 of the bushing 14, member 29 being substantially sleeve-like, having an in-

side surface substantially cylindrical and extending vertically, and having an upper threaded portion 29^a. The gaseous dielectric within the casting 10 extends upwardly into the members 14 and 29.

15 In threaded engagement with portion 29^a of the sleeve member 29 is a tubular housing 30 made preferably of a phenolic condensation product or bakelite but closed at its upper end by means of a metallic plug 31 in threaded engagement therewith; plug 31 has extending therethrough a tubular conductor 32, conductor 32 extending downwardly and coaxially with the interior cylindrical surface of sleeve member 29 and extending also upwardly and out of the plug 31.

25 The upper outer portion of tubular conductor 32 is threaded as at 32^a to receive a nut 33 for clamping the lower end of the connector 26 into electrical connection with the tubular conductor 32. The latter is closed or sealed at its upper end, as at 34, and conveniently the sealing means 34 has the end of conductor 13 embedded therein. This sealing means may comprise a plug made of any suitable metal.

The bakelite housing 30 is preferably tapered somewhat, as shown in the drawing, and is of sufficient thickness to withstand the pressure of the gaseous dielectric which extends into the space between tubular conductor 32 and the inside of housing 30 and which coacts with the latter in achieving dependable insulation of the high tension conductor 32 from the casing 10 and associated metallic parts.

The threaded connections between the bakelite housing 30 and the members 29 and 31 are also of a mechanical strength adequate to withstand this pressure of the gaseous dielectric and preferably are sealed by means of a permanently elastic and resilient cement. The housing 30 is of an axial length and also of a thickness adequate to withstand the dielectric stress to which it is subjected, but these dimensions are much less than they would be otherwise, due to the coaction with the solid dielectric housing 30 of the gaseous dielectric under pressure and of certain other parts of the apparatus.

More particularly, the construction thus indicated as a whole at 28 is such that in the field of highest voltage gradient, namely, the field that exists between the sleeve-like bushing 29 (at ground potential) and the tubular conductor 32 (at the high potential) is in the layer of gaseous dielectric between these two parts; the gaseous dielectric under pressure on the order of fifteen atmospheres or so has very great dielectric strength and can best withstand this high voltage gradient and do so, more particularly, without requiring an unwieldy mass or impracticable dimensions.

The bakelite housing 30, tapered both interiorly and exteriorly and less capable of withstanding high voltage gradients, is disposed, due to its shape, in the field of lowest voltage gradient, generally in the field extending from the plug 31 to the grounded ring member 19. In fields of intermediate voltage gradient, there exists

both gaseous dielectric under pressure and the solid dielectric of member 30, these dielectrics being in series, the series relation causing the two dielectrics to assume dielectric stresses in inverse proportion to their permittivities; thus the solid dielectric 30, having a much greater permittivity than the gaseous dielectric under pressure is relieved from assuming too great a stress. Furthermore, the gaseous dielectric under pressure vastly increases the resistance to surface leakage along the inside surface of member 30 in a direction from plug 31 to sleeve 29.

80 The above-described construction 28 thus compactly and dependably supports and carries the high tension conductor 32 through the opening in the wall of the casing 10, utilizing as an important factor the gaseous dielectric under pressure, while at the same time it dependably seals the casing 10 against escape of the gaseous dielectric, the bakelite member 30 being impervious and having so high a tensile strength that undue bulk or volume thereof is avoided.

85 The upper plate member 23 is provided with a threaded opening 35 through which the space between the interior wall of member 21 and the parts contained therein is filled with an insulating medium of a character that may be poured into this space upon heating and that will harden or solidify upon cooling. A suitable material for this purpose is halowax which, upon being heated, 90 may be readily poured in through the opening 35 which is thereupon closed by a threaded plug 36, the halowax, upon cooling, assuming a plastic form. This insulating medium is indicated at 95 37. Halowax is a chloronaphthalene substitution product. The halowax, when cool, becomes substantially rigid and may thus be classified as a solid dielectric material; moreover, the halowax enters all of the irregularities, recesses, and the like, of the peculiarly shaped space between the 100 outer tube-like member and the inner tube-like member 28, thus becoming interlocked with each and thus interlocking these two members themselves.

105 The insulating medium 37 insures that no moisture can get to the structure 28 even if leakage through the member 23 or through any of the joints between members 23, 21 and 19 were to take place, and it also greatly minimizes the possibility of surface leakage along the interior 110 wall of member 21 and along the exterior surface of member 30. Aside from such coactions as these, insulating medium 37 is also interposed in certain portions of the dielectric field and coacts with the other dielectrics in achieving dependable insulation of the high tension conductor 115 from the grounded casing 10.

120 The conductor 32, it will be noted, presents a cylindrical surface that is concentric with the inside surface of member 29; these surfaces are 125 of such radii as to form a fast discharge gap across which break-down occurs without being preceded by corona; the action of the gap is thus instantaneous. The critical voltage of the gap is such that it breaks down at a voltage less than 130 that which will injure any of the associated devices or apparatus. For example, I may give it a critical voltage such that it will break-down when, for any reason, the voltage, either transient or otherwise, impressed upon conductor 27 and 135 hence upon member 23, is greater than that which will cause break-down of any of the insulating part or parts of the structure above-described or which will cause injury to the apparatus within the casing 10.

Member 19 is threaded as at 19^a and has an inside diameter at this portion somewhat greater than the greatest outside diameter of bakelite housing 30. Before assembling the housing 30 and/or sleeve member 29 with respect to the bushing 14, there is threaded upon the threaded portion 18 thereof a collar 38 which is externally threaded. After members 29 and 30 have been assembled with respect to bushing 14, ring member 19 is slipped down over the housing 30 and is threaded onto the collar 38, whence the assembly may proceed as will be clear from the foregoing.

It will thus be seen that there has been provided in this invention a high voltage outdoor terminal construction in which the various objects hereinbefore noted, together with many thoroughly practical advantages, are successfully achieved.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. In high voltage terminal construction, in combination, a casing having therein an electrical apparatus and a gaseous dielectric under pressure and having an opening through which a high voltage conductor is to be passed, a metallic bushing externally threaded and forming an extension of said opening, a ring-like member in threaded engagement with said bushing, a sleeve-like insulator made of a material adapted to withstand weather supported by said ring-like member and having its upper end sealed and provided with means for connecting thereto a high voltage circuit, a high voltage conductor in connection at its upper end with said connecting means and extending through said bushing into said casing, and means for insulatingly supporting said conductor and sealing said opening, said means including a sleeve-like member made of phenolic condensation product supported at its lower end by said bushing and sealed thereto and having said conductor passing through its upper end and in sealed connection therewith, said gaseous dielectric extending into the space between said conductor and said second-mentioned sleeve-like member, and an insulating compound filling the space between said two insulating sleeve-like members, the radii of said bushing and said conductor being proportioned so as to form a fast discharge gap adapted to break-down at a critical voltage less than that which would injure one of said insulating sleeve-like members, and said ring-like member having an inside diameter greater than the maximum outside diameter of said second-mentioned sleeve-like insulating member.

2. In high voltage terminal construction, in combination, a casing having therein an electrical apparatus and a gaseous dielectric under pressure and having an opening through which a high voltage conductor is to be passed, a metallic bushing externally threaded and forming an extension of said opening, a ring-like member in threaded engagement with said bushing, a sleeve-like insulator made of a material adapted to withstand weather supported by said ring-like member and having its upper end sealed and provided with means for connecting thereto a high voltage circuit, a high voltage conductor

in connection at its upper end with said connecting means and extending through said bushing into said casing, and means for insulatingly supporting said conductor and sealing said opening, said means including a sleeve-like member made of phenolic condensation product supported at its lower end by said bushing and sealed thereto and having said conductor passing through its upper end and in sealed connection therewith, said gaseous dielectric extending into the space between said conductor and said second-mentioned sleeve-like member.

3. In high voltage terminal construction, in combination, a casing having therein an electrical apparatus and a gaseous dielectric under pressure and having an opening through which a high voltage conductor is to be passed, a metallic bushing externally threaded and forming an extension of said opening, a ring-like member in threaded engagement with said bushing, a sleeve-like insulator made of a material adapted to withstand weather supported by said ring-like member and having its upper end sealed and provided with means for connecting thereto a high voltage circuit, a high voltage conductor in connection at its upper end with said connecting means and extending through said bushing into said casing, and means for insulatingly supporting said conductor and sealing said opening, said means including a sleeve-like member made of phenolic condensation product supported at its lower end by said bushing and sealed thereto and having said conductor passing through its upper end and in sealed connection therewith, said gaseous dielectric extending into the space between said conductor and said second-mentioned sleeve-like member, and an insulating compound filling the space between said two insulating sleeve-like members, the radii of said bushing and said conductor being proportioned so as to form a fast discharge gap adapted to break-down at a critical voltage less than that which would injure one of said insulating sleeve-like members.

4. In high voltage terminal construction, in combination, a casing having therein an electrical apparatus and a gaseous dielectric under pressure and having an opening through which a high voltage conductor is to be passed, a metallic bushing externally threaded and forming an extension of said opening, a ring-like member in threaded engagement with said bushing, a sleeve-like insulator made of a material adapted to withstand weather supported by said ring-like member and having its upper end sealed and provided with means for connecting thereto a high voltage circuit, a high voltage conductor in connection at its upper end with said connecting means and extending through said bushing into said casing, and means for insulatingly supporting said conductor and sealing said opening, said means including insulating means in sealed connection with both said high voltage conductor and said bushing and contained within said sleeve-like insulating member.

5. In high voltage terminal construction, in combination, a casing having therein an electrical apparatus and a gaseous dielectric under pressure and having an opening through which a high voltage conductor is to be passed, a metallic bushing externally threaded and forming an extension of said opening, a ring-like member in threaded engagement with said bushing, a sleeve-like insulator made of a material adapted to withstand weather supported

- by said ring-like member and having its upper end sealed and provided with means for connecting thereto a high voltage circuit, a high voltage conductor in connection at its upper end with said connecting means and extending through said bushing into said casing, and means for insulatingly supporting said conductor and sealing said opening, said means including an insulating member in sealed connection with both said high tension conductor and said bushing and made of a material poorly adapted to withstand weather and contained within said sleeve-like insulator. 5 80
6. In high voltage terminal construction, in combination, a casing having therein an electrical apparatus and a gaseous dielectric under pressure and having an opening through which a high voltage conductor is to be passed, a metallic bushing externally threaded and forming an extension of said opening, a ring-like member in threaded engagement with said bushing, a sleeve-like insulator made of a material adapted to withstand weather supported by said ring-like member and having its upper end sealed and provided with means for connecting thereto a high voltage circuit, a high voltage conductor in connection at its upper end with said connecting means and extending through said bushing into said casing, means for insulatingly supporting said conductor and sealing said opening, said means including an insulating member in sealed connection with both said high tension conductor and said bushing and made of a material poorly adapted to withstand weather and contained within said sleeve-like insulator, and a dielectric filling the space between said two insulating members. 10 15 20 25 30 35 40 45 50 55 60 65 70 75 85 90 95 100 105 110 115 120 125 130 135 140 145 150
7. In high voltage terminal construction, in combination, a casing having therein an electrical apparatus and a gaseous dielectric under pressure and having an opening through which a high voltage conductor is to be passed, a metallic bushing externally threaded and forming an extension of said opening, a ring-like member in threaded engagement with said bushing, a sleeve-like insulator made of a material adapted to withstand weather supported by said ring-like member and having its upper end sealed and provided with means for connecting thereto a high voltage circuit, a high voltage conductor in connection at its upper end with said connecting means and extending through said bushing into said casing, and means for insulatingly supporting said conductor and sealing said opening, said means including a sleeve-like member made of phenolic condensation product supported at its lower end by said bushing and sealed thereto and having said conductor passing through its upper end and in sealed connection therewith, said gaseous dielectric extending into the space between said conductor and said second-mentioned sleeve-like member, and an insulating medium impervious to moisture and filling the space between said two sleeve-like insulating members. 11 120 125 130 135 140 145 150
8. In high voltage terminal construction, in combination, a casing having therein an electrical apparatus and a gaseous dielectric under pressure and having an opening through which a high voltage conductor is to be passed, a high voltage tube-like insulating member made of a material adapted to withstand weather, means forming a sealed connection between one end of said member and said casing, means forming a high voltage conductor extending from the other end of said member through said opening, a tube-like member of phenolic condensation product extending upwardly into said first-mentioned tube-like member and having one end thereof in sealed connection with said casing and the other end thereof in sealed connection with said high voltage conductor, said second-mentioned tube-like member being of a radius and wall thickness to withstand the pressure of said gaseous dielectric, thereby to prevent said first-mentioned tube-like member from being subjected to said pressure. 15 20 25 30 35 40 45 50 55 60 65 70 75 80 85 90 95 100 105 110 115 120 125 130 135 140 145 150
9. In high voltage terminal construction, in combination, a casing having therein an electrical apparatus and a gaseous dielectric under pressure and having an opening through which a high voltage conductor is to be passed, a high voltage tube-like insulating member made of a material adapted to withstand weather, means forming a sealed connection between one end of said member and said casing, means forming a high voltage conductor extending from the other end of said member through said opening, and means in sealed connection with said casing and with said conductor for preventing access of said gaseous dielectric under pressure to the interior of said insulating member, thereby preventing the latter from being subjected to the high pressure of said gaseous dielectric, said last-mentioned means being made of a solid dielectric material adapted to withstand high pressures. 15 20 25 30 35 40 45 50 55 60 65 70 75 80 85 90 95 100 105 110 115 120 125 130 135 140 145 150

- thereby to prevent said first-mentioned tube-like member from being subjected to said pressure, and a solid dielectric medium filling the space between said two tube-like members.
- 5 12. In high voltage terminal construction, in combination, a casing having therein an electrical apparatus and a gaseous dielectric under pressure and having an opening through which a high voltage conductor is to be passed, and two concentric substantially tubular insulating members, one within the other, a high voltage conductor extending through said two members and into said opening, means forming a sealed connection between one end of the inside tubular member and said casing, means forming a sealed connection between the other end of said inside tubular member and said conductor, said inside tubular member being made of an insulating material adapted to withstand the pressure of said gaseous dielectric and having a wall thickness and radius sufficient to resist the said pressure, thereby to prevent said outside tubular member from being subjected to said pressure, and said outside tubular member being made of a solid dielectric material adapted to withstand weather, and means engaging that end of said outside tubular member that is nearest said casing for holding it in assembled relation to said inner tubular member.
- 10 13. In high voltage terminal construction, in combination, a casing having therein an electrical apparatus and a gaseous dielectric under pressure and having an opening through which a high voltage conductor is to be passed, and two concentric substantially tubular insulating members, one within the other, a high voltage conductor extending through said two members and into said opening, means forming a sealed connection between one end of the inside tubular member and said casing, means forming a sealed connection between the other end of said inside tubular member and said conductor, said inside tubular member being made of an insulating material adapted to withstand the pressure of said gaseous dielectric and having a wall thickness, and radius sufficient to resist the said pressure, thereby to prevent said outside tubular member from being subjected to said pressure, the space between said conductor and the interior of said inside tubular member being filled with gaseous dielectric under pressure, and the space between said two tubular members being filled with a solid dielectric medium.
- 15 14. In high voltage terminal construction, in combination, a casing having therein an electrical apparatus and a gaseous dielectric under pressure and having an opening through which a high voltage conductor is to be passed, and two concentric substantially tubular insulating members, one within the other, a high voltage conductor extending through said two members and into said opening, means forming a sealed connection between one end of the inside tubular member and said casing, means forming a sealed connection between the other end of said inside tubular member and said conductor, said inside tubular member being made of an insulating material adapted to withstand the pressure of said gaseous dielectric and having a wall thickness and radius sufficient to resist the said pressure, thereby to prevent said outside tubular member from being subjected to said pressure, said inside tubular member having external dimensions adapted to resist flash-over from said conductor to said casing at substantially operating voltages and said external
- tubular member having external dimensions adapted to withstand flash-over to said casing under weather conditions, and means forming sealed connections between the adjacent ends of said two tubular members.
- 20 15. In high voltage terminal construction, in combination, a casing having therein an electrical apparatus and a gaseous dielectric under pressure and having an opening through which a high voltage conductor is to be passed, and two concentric substantially tubular insulating members, one within the other, a high voltage conductor extending through said two members and into said opening, means forming a sealed connection between one end of the inside tubular member and said casing, means forming a sealed connection between the other end of said inside tubular member and said conductor, said inside tubular member being made of an insulating material adapted to withstand the pressure of said gaseous dielectric and having a wall thickness and radius sufficient to resist the said pressure, thereby to prevent said outside tubular member from being subjected to said pressure, said inside tubular member being made of phenolic condensation product and said outside tubular member being made of a ceramic material and having a greater length of external surface than said inside tubular member.
- 25 16. In high voltage terminal construction in combination, a wall member having an opening through which a high voltage conductor is to be passed, a high voltage conductor extending through said opening, and means for insulatingly supporting said high voltage conductor, said means including a plurality of tube-like insulators, one within the other, the innermost insulator having an inside diameter larger than the outside diameter of said conductor, thereby to form a space therebetween an inside insulator being made of phenolic condensation product and the outermost insulator being made of a material adapted to withstand weather, and solid dielectric means in mechanical interlocking relation with both of said insulators.
- 30 17. In high voltage terminal construction, in combination, a wall member having an opening through which a high voltage conductor is to be passed, a high voltage conductor extending through said opening, and means for supporting and insulating said high voltage conductor from said wall, said means including a gaseous dielectric under pressure, solid dielectric means mechanically supporting said conductor and adapted to withstand the pressure of said gaseous dielectric, and an outer exposed insulating means enveloping and interlocked with said first-mentioned insulating means and having exposed portions made of a material adapted to withstand weather.
- 35 18. In high voltage terminal construction, in combination, a wall member having an opening through which a high voltage conductor is to be passed, a high voltage conductor extending through said opening, and means for supporting and insulating said high voltage conductor from said wall, said means including a gaseous dielectric under pressure, solid dielectric means mechanically supporting said conductor and adapted to withstand the pressure of said gaseous dielectric, means made of a refractory material encompassing said insulating means and sealing the latter against exposure to weather, and means acting independently of said conductor for securing said refractory means in place.

19. In high voltage terminal construction, in combination, a wall member having an opening through which a high voltage conductor is to be passed, a high voltage conductor extending 5 through said opening, means for insulatingly supporting said high voltage conductor, said means including a plurality of tube-like insulators, one within the other, the innermost insulator having its inside walls spaced from said conductor, a fluid 10 dielectric filling the said space between said conductor and said innermost insulator, an inside insulator being made of phenolic condensation product and the outermost insulator being made of a material adapted to withstand weather, and 15 an intermediate insulator being made of a plastic material that is solid at ordinary operating temperatures.
20. In high voltage terminal construction, in combination, metallic bushing means adapted to 20 be related to an opening in a wall member, a conductor extending through said bushing means and spaced from the walls thereof, means of solid dielectric material forming a sealed connection between said conductor and an end of said bushing 25 means and holding said conductor spaced from the walls of said bushing means, said solid dielectric means being substantially tubular and said bushing means having a threaded portion of greater diameter than the outside diameter of said tubular dielectric means, a sleeve-like solid dielectric member adapted to be slipped over said tubular means, and a threaded ring member at one 30 end of said sleeve-like member in threaded engagement with said threaded portion of said bushing means.
21. In high voltage terminal construction, in combination, metallic bushing means adapted to be related to an opening in a wall member, a conductor extending through said bushing means and spaced from the walls thereof, means of solid dielectric material forming a sealed connection between said conductor and an end of said bushing means and holding said conductor spaced from the walls of said bushing means, said bushing 40 means having a portion projecting laterally beyond said solid dielectric means, and insulating means shaped to encompass said solid dielectric means and having mounting means adapted to be passed over said solid dielectric means and into engagement with said projecting part of said bushing means.
22. In high voltage terminal construction, in combination, a bushing interiorly threaded and having a portion exteriorly threaded, a conductor 50 passing through said bushing and spaced from the walls thereof, solid dielectric means supported from the interiorly threaded portion of said bushing and holding said conductor in said spaced
- relation, and solid dielectric means adapted to withstand weather encompassing said first-mentioned solid dielectric means and supported by said exteriorly threaded portion of said bushing. 55
23. In high voltage terminal construction, in combination, a bushing having an interiorly threaded part and an exteriorly threaded part; a rigid conductor extending through said bushing but spaced from the walls thereof; means supporting and insulating said conductor from said bushing comprising a metallic bushing threaded to said interiorly threaded part of said first bushing and having a tube-like housing of organic solid dielectric material secured thereto, said conductor being supported by and extending through said housing; and a solid dielectric housing made of a refractory material encompassing said first-mentioned housing and supported by said exteriorly threaded part of said first bushing. 60
24. In high voltage terminal construction, in combination, a bushing having an interiorly threaded part and an exteriorly threaded part; a rigid conductor extending through said bushing but spaced from the walls thereof; means supporting and insulating said conductor from said bushing comprising a metallic bushing threaded to said interiorly threaded part of said first bushing and having a tube-like housing of organic solid dielectric material secured thereto, said conductor being supported by and extending through said housing; and a solid dielectric housing made of a refractory material encompassing said first-mentioned housing and supported by said exteriorly threaded part of said first bushing. 65
25. In high voltage terminal construction, in combination, a bushing having an interiorly threaded part and an exteriorly threaded part; a rigid conductor extending through said bushing but spaced from the walls thereof; means supporting and insulating said conductor from said bushing comprising a metallic bushing threaded to said interiorly threaded part of said first bushing and having a tube-like housing of organic solid dielectric material secured thereto, said conductor being supported by and extending through said housing; and a solid dielectric housing adapted to encompass said first housing; and a metallic annulus in threaded engagement with said exteriorly threaded part of said first bushing and having said second housing secured thereto. 70

FRANKLIN S. SMITH.
